UNITED STATES PATENT OFFICE.

VICTOR L. BONCI, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed July 30, 1924. Serial No. 729,016.

This invention relates to electron discharge devices and pertains more especially to the evacuation of such devices.

In devices of this character it is preferable to complete the evacuation of the vessel by vaporizing a reducing medium or getter, such as calcium or magnesium, to absorb the remaining gas. This process consists of flashing or otherwise heating the reducing medium to the vaporization point whereby the vapor absorbs the gases and deposits in the form of a silvery coating or film on the interior wall of the vessel. Due to the spreading of the vapor of the reducing medium over the entire wall of the vessel, a view of the electrodes is completely obstructed. In vacuum tubes used in repeater installations, which are under constant observation, the coating is quite detrimental to the observation of the tubes, since the attendant cannot observe the spacing of the electrodes nor detect other defects within the tubes. Furthermore, this coating prevents the free dissipation of heat in the vessel since the heat is reflected from the mirror-like coating and remains in the vessel thereby subjecting the electrodes to excessive heat which in time will break down the thermionically active coatings on the electrodes and reduce their efficiency.

It is an object of this invention to limit the deposit of the getter to a relatively small portion of the glass vessel.

In accordance with this invention these disadvantages are eliminated by carrying the reducing medium or getter in a circular tubing having a slit on its periphery, which is supported from the electrode assembly. When the reducing medium is heated, the vapor is emitted from the slit and deposits in a ring or halo of restricted area on the side wall of the vessel. The control of the vapor, whereby the vapor film is forced to deposit in the form of a ring on the vessel wall, provides a clear view of the electrode structure from the top and sides of the vessel, whereby any defects in the electrodes themselves can be detected. Also the heat generated by the device is more easily dissipated through the clear wall of the vessel since the restricted area covered by the coating does not prevent the generated heat radiating through the glass vessel.

Referring to the drawings, Fig. 1 shows an electron discharge device with parts

broken away to illustrate the invention. Fig. 2 is an enlarged sectional view of the control-line device made in accordance with this invention.

The electron discharge device to which this invention is particularly applicable consists of a glass enclosing vessel 10 having an inwardly projected stem 11. A cylindrical metallic base 12 is cemented to the glass vessel whereby the device may be inserted in a vacuum tube socket in any well known manner. A flattened cylindrical plate electrode 13 is supported within the vessel by the metallic arms 14 attached to a metallic collar 15 surrounding the stem 11. The insulating blocks 16 and 17 are supported at the upper and lower ends of the plate electrode by integral projections carried by the plate. A grid electrode 18 and an oxide-coated filament 19 are positioned within the plate electrode and supported from the insulating blocks 16 and 17.

Attached to the upper insulating block 16 is a metallic rod 20 passing through an aperture in the insulating block, one end of the rod 20 being passed through a parallel aperture and bent at 21, at right angles to the shank of the rod 20, forming an anchor therefor. The free end of the rod 20 is attached to a circular closed ring 22, preferably by spot welding. The ring 22 is preferably made of nickel, although other metals may be used, and is formed from tubing and provided with a peripheral slit or opening 23. The supporting rod 20 is attached to the ring 22 on the inner circumference of the ring so that the opening 23 will not be obstructed at this point. A reducing medium 24, which may consist of calcium, magnesium or any other alkaline earth metal, is inserted in the hollow tubing and thereby effectively supported within the glass vessel.

The preliminary steps in the evacuation process consist of denuding the electrodes of the occluded gases by bombardment or in any well known manner; the gases being carried away by a mercury vacuum pump or the like. This process, however, does not remove all the gases and it is necessary to vaporize a reducing medium which will fix the gases in the vessel and thereby obtain a high vacuum. Since the heat generated by the bombardment of the electrodes is insufficient to vaporize the reducing medium, it

has been found preferable to flash the reducing medium by inducing current in the ring 22 by high frequency alternating current supplied from a high frequency thermionic oscillator, such as described in M. J. Kelly U. S. Patent 1,565,857, Serial No. 481,610, issued December 15, 1925, entitled: "Vacuum tube manufacture," since by this method the vaporization of the medium is 10 accomplished in a very short period. Furthermore, the high frequency method can be very easily controlled.

In accordance with this invention a high frequency coil, shown and described in the 15 co-pending application mentioned above, surrounds the glass vessel adjacent to the portion of the vessel occupied by the reducing medium. The induced currents from the high frequency source supplies sufficient 20 heat in the closed ring 22 to vaporize the reducing medium within the ring whereby the vapor absorbs the residual gas and deposits on the vessel wall. The vapor can only be emitted from the ring 22 through 25 the slit 23. Therefore, due to the limited outlet provided by the slit in the ring, the vapor in its travel from the ring to the

glass wall will only cover a limited area shown by the dotted portion 25. Since the vapor film is restricted to a certain area in 30 the vessel it is apparent that visual observation of the spacing of the electrode can be obtained, and furthermore, that the coating does not materially lessen the radiating surface of the vessel whereby the internal heat 35 can be dissipated.

Although the invention has been shown and described in a particular form it is apparent that various modifications may be made in the structural details without departing from the scope of the invention as set forth in the appended claim.

What is claimed is:

An electron discharge device comprising an evacuated vessel, an electrode assembly, a 45 hollow ring having an opening in its outermost circumference, said ring being supported from said assembly near the top of the vessel and a vaporizable reducing medium within said ring.

In witness whereof, I hereunto subscribe my name this 25th day of July, A. D. 1924.

VICTOR L. RONCI.
